UNITED STATES PATENT OFFICE.

FRIEDRICH OSMER, OF BROOKLYN, NEW YORK, ASSIGNOR OF ONE-THIRD
TO MATTHIAS HOPKE, OF SAME PLACE.

APPARATUS FOR TAKING OFF AMMONIA FROM BONE-BLACK RETORTS.

SPECIFICATION forming part of Letters Patent No. 297,948, dated April 29, 1884.

Application filed December 5, 1883. (No model.)

To all whom it may concern:

Be it known that I, FRIEDRICH OSMER, of the city of Brooklyn, in the county of Kings and State of New York, have invented a new 5 and useful Improvement in Apparatus for Taking Off Ammonia from Bone-Black Retorts, of which the following is a specification.

The retorts commonly used for reburning or revivifying bone-black or "char" are set in 10 an upright position, and the char is fed into them from a feeding floor or plate at their upper open ends, the retorts being kept constantly filled with the char, and the char gravitating downward as it is removed from time 15 to time at the lower ends of the retorts. The char contains ammonia in considerable quantities, which is volatilized in the lower and hotter parts of the retort and passes upward through the char; and my invention relates to 20 means which are employed to allow the ammonia to escape freely from the upper end of the retort without passing through the pile of char above the retort. The retorts which are used for reburning char are oblong in their 25 transverse section, the major diameter being several times greater than the minor diameter, the larger retorts being about twenty-four inches by four inches in size, and the smaller sizes being from twelve to eight inches in their 30 larger diameter, and from two and one-half to two inches in their lesser diameter.

In my Letters Patent of the United States No. 287,570, and bearing date October 30, 1883, I have shown and described a means for taking off the ammonia, which consists in inserting within the upper end of the retort a feeding-throat smaller in size than the retort, so as to leave a passage or space, which extends all around between the feeding-throat and the 40 inner wall of the retort, and which forms a flue for the escape of the ammonia. While I consider the above-described construction as most desirable for the larger retorts, which are about four inches wide, it is somewhat objectionable for the medium or smaller retorts, which are only about two or two and one-half inches wide, because the width of the flue or space on the two sides of the feeding-throat, added to the thickness of the walls of said 45 throat, renders it impossible to make the feed-

ing-throat much if anything more than one inch wide; hence the char must all be introduced into the retort through a throat which is only about one inch wide, and attention is necessary to prevent the char from clogging 55 or choking up the feeding-throat, especially when the char is wet.

My present invention is more particularly intended for retorts of the smaller sizes; and the object is to allow an opening for the introduction of char sufficient in size to avoid 60 clogging or choking of said opening and to still allow for the escape of ammonia without its passing through the pile of char at the top of the retort.

To this end the invention consists, essentially, in the combination, with a retort of oblong transverse section, of a flue of oblong transverse section arranged within the retort for conducting away the volatilized ammonia, the said retort being extended considerably beyond the said flue in the direction of their major axes, whereby there is afforded an ample opening for the feeding of char into the 70 retort.

The invention also consists in the combination, with the retort and flue above described, of bearers, whereby the said flue is supported on the feeding-floor above the retort, whereby I am enabled to apply an escape-flue of the 75 kind above described to any retort of a proper size to receive it, by simply inserting the flue downward into the retort.

The invention also consists in other details of construction and combinations of parts hereinafter described and referred to in the claims.

In the accompanying drawings, Figure 1 is a vertical section of the upper portion of two retorts and flues embodying my invention, together with a portion of the feeding-floor. 85 Fig. 2 is a vertical section on the dotted line *x x*, Fig. 1; and Fig. 3 is a horizontal section of the retorts and flues on the plane of the dotted line *y y*, Fig. 1.

Similar letters of reference designate corresponding parts in all the figures.

A designates the retorts, which are of the usual form, oblong in transverse section, and which are heated by a furnace. (Not here shown.)

At the upper end of the retorts is the usual plate, B, surmounted by brick-work B', on which is placed the usual feeding plate or floor, C. 5 C designates feeding-throats extending from the floor C into the retorts. D designates the flues for conducting away the volatilized ammonia, one flue being arranged in each retort; and these flues are connected at their upper ends with a pipe, E, whereby the volatilized ammonia may be conducted to a condenser or water-tank and there absorbed. The flues D may be constructed of cast-iron or other suitable material, and 10 that portion of the flue which enters the retort is of oblong transverse section, as best shown in Fig. 3. The flues D are provided with ribs or projections a, extending from opposite sides, as shown in Figs. 1 and 3, and are likewise 15 provided with other ribs or projections, a', extending from them in the direction of their major diameter, as shown in Figs. 2 and 3. These ribs or projections may be cast integral with the flues, and serve to hold the flues in proper 20 central position within the feeding-throats C' and retorts A. The flues D are or may be supported by bearers which rest upon the feeding-floor C. As here shown, the flues are supported 25 by bearers consisting of bars F, which extend across the floor C from one to the other of the flues and to which the flues are secured at e. Being thus supported, the flues D can be readily removed from the retorts by simply 30 raising them, and can be as readily applied to or inserted into any retorts which are of the proper size. The feeding-opening for char 35 extends entirely around the flue D, as shown in Fig. 3; but those portions d of the opening which are at the sides of the flue are very 40 narrow, and if so narrow an opening extended entirely around the flue D, the char would be liable to clog and choke up the opening. To 45 obviate this clogging or choking of the feeding-opening of the retort, I extend the retort A, in the direction of its major axis, very much beyond the flue D; or, in other words, I make the major diameter of the flue very much less than the major diameter of the retort, and I thus greatly increase the size of the opening 50 between the flue and retort, by providing said

opening with the enlargements d'. Such enlargements d' are nearly as wide as the retort itself, and afford an ample opening for feeding char without danger of the char clogging or choking the opening. 55

In order to afford still greater facility for the free escape of the ammonia, I may provide the flues D with openings e, through which ammonia can pass from the exterior of the flue to its interior, as shown by the arrows in Figs. 1 and 2; and in order to prevent these holes e from being clogged by char, I protect them by hoods e', formed on or secured to the exterior of said flues. 60

The holes e and hoods e' may be arranged 65 at different levels, as shown in Figs. 1 and 2. In addition to taking off ammonia, the flues D will serve to conduct away other noxious gases evolved by heat.

What I claim as my invention, and desire to 70 secure by Letters Patent, is—

1. The combination, with a retort of oblong transverse section, of a flue, also of oblong transverse section, arranged within the retort for conducting away the ammonia or other 75 noxious gases, the said retort being extended considerably beyond the flue in the direction of their major axes, substantially as and for the purpose herein described.

2. The combination, with the retort and flue, 80 both being oblong in their transverse section, and the retort being extended considerably beyond the flue in the direction of their major axes, of the feeding floor or plate, and bearers secured to the flue and serving to support the same by resting on said floor or plate, substantially as and for the purpose herein described.

3. The combination, with the retort A, of oblong transverse section, of the flue D, also of oblong transverse section, and provided 90 with escape-holes e and with hoods e' on its exterior, the said retort being extended considerably beyond the flue in the direction of their major axes, substantially as and for the purpose herein described.

FRIEDRICH OSMER.
